UNITED STATES PATENT OFFICE

121,392

DESIGN FOR A COOLER CABINET

Raymond Loewy and A Baker Barnhart, New York, N. Y., assignors to The Coca-Cola Company, Wilmington, Del., a corporation of Delaware

Application October 24, 1939, Serial No. 87,836

Term of patent 14 years

To all whom it may concern:

Be it known that we, Raymond Loewy and A Baker Barnhart, citizens of the United States and residents of New York, New York County, New York, have invented a new, original, and ornamental Design for Cooler Cabinets, of which the following is a specification, reference being had to the accompanying drawings, forming part thereof.

Fig. 1 is a perspective view of the cooler cabinet, showing our design;

Fig. 2 is a front elevational view;

Fig. 3 is a rear perspective view; and
Fig. 4 is a rear elevational view thereof;
Fig. 5 is an end elevational view, said view being taken from the right of Fig. 1; and
Fig. 6 is an end elevational view, said view being taken from the left of Fig. 1;
Fig. 7 is a top plan view of the cooler cabinet.

We claim:

The ornamental design for a cooler cabinet, as shown.

RAYMOND LOEWY.
A BAKER BARNHART.
